UNITED STATES PATENT OFFICE

THOMAS CARNEY, OF DAYTON, OHIO, ASSIGNOR TO THE NATIONAL CASH REGISTER COMPANY, OF SAME PLACE.

COIN-DISPLAYER.

SPECIFICATION forming part of Letters Patent No. 484,650, dated October 18, 1892.

Application filed July 12, 1892. Serial No. 439,810. (No model.)

To all whom it may concern:

Be it known that I, THOMAS CARNEY, a citizen of the United States, residing at Dayton, in the county of Montgomery and State of Ohio, have invented certain new and useful Improvements in Coin-Displayers, of which the following is a description, reference being had to the accompanying drawings, forming part of this specification.

10 My invention relates to devices of that class which are employed for the purpose of receiving and temporarily exposing to view the various coins received by the clerk or cashier in an establishment where the devices are used. Their principal object is to prevent disputes concerning the character or values of coins received from customers, though it is sometimes desirable for other purposes to temporarily hold the coins received exposed 15 to view. The devices may be used either alone or in combination with other contrivances employed in the handling and disposition of the cash received.

20 My improved coin-displayer is especially designed to be used in connection with a cash-register and to be operated automatically by such machine. In the accompanying drawings I have illustrated it as applied to one of the well-known forms of cash-registers and arranged to co-operate with and be actuated by the sliding money-drawer of such machine, and it will be described, in combination with such machine, in the following specification. Its novelty will be herein set forth, and particularly pointed out in the claims.

25 In the drawings, Figure 1 is a perspective view of a cash-register having my improved coin-displayer applied to it; Fig. 2, a vertical section through part of the frame or casing 30 of the coin-displayer and through the drawer-compartment and drawer of the register, as indicated by the dotted line 22 in Fig. 3; Fig. 3, a vertical section through the coin-displayer and one side of the drawer-compartment and drawer on the line 33 of Fig. 2, and Fig. 4 a side elevation of the coin-receiving disk having the glass plates secured to its sides and provided with a ratchet for turning it.

35 40 The same letters of reference are used to indicate identical parts in all the figures.

My improved device consists of a suitable frame or casing having a receiving mouth or opening into which the coins may be dropped and a discharging mouth or opening through which they may be discharged from the device into any suitable receptacle—in this instance into the money-drawer of a cash-register. Journaled in the casing or frame is a revolving disk provided with holes or recesses arranged around its periphery and intersecting the latter, which holes or recesses constitute the receptacles for the coins, being adapted to receive the coins at the receiving-mouth of the casing and carry them around and deliver them at the discharging-mouth thereof. These holes or recesses are covered at one side and, if desired, at both sides of the disk by a glass plate or plates, through which the coins contained in the receptacles may be observed from the exterior. Such glass plate or plates may be secured to the side or sides of the revolving disk or they may form a fixed part of the casing, as desired, or each separate receptacle may be covered by its own individual transparent plate.

45 In the drawings I have shown the coin-receptacle as formed of circular holes extending entirely through the disk and intersecting its periphery at such a distance from their centers as to form suitable openings for the reception and discharge of the coins. I have shown the sides of these holes as closed by two circular glass plates, secured to the opposite sides of the disk, so that when the device is used alone the coins in it may be observed from either side. I have shown the revolving disk provided with a ratchet, with which co-operates a pawl carried by a lever which projects through the base of the machine into the drawer-compartment into position to be engaged and moved by the money-drawer or some part carried thereby, though any other suitable form of connection of the revolving disk, either with the money-drawer or any other part of the cash-register which is moved at each operation of the machine, may be employed.

50 Referring now more particularly to the accompanying drawings, it will be seen that the casing or frame A of the coin-displayer

is secured to the top of the drawer-compartment of the cash-register, which has an opening B beneath the display for the passage of the coins into the drawer. The casing of 5 the display is shown in this instance as formed of two halves, each consisting of an upright standard portion, an annular portion for the reception of the revolving disk, and one-half of the receiving mouth or opening 10 in which the coins are deposited. The two halves of the casing are secured together at their upper sides by a screw passed through ears on them and at their lower sides by cross-rods A². Fast upon a shaft or spindle 15 C, journaled at its ends in the uprights or standards of the frame, is the revolving disk D, provided with the series of circular holes E, extending through it and intersecting its periphery. This disk has secured upon its 20 opposite sides two circular glass plates F. The peripheries of the disk and these circular plates fit snugly within the annular portion of the casing A, which latter prevents the coins escaping from the receptacles formed 25 by the holes and the glass plates until the receptacles are brought opposite the discharging-mouth of the casing. Fast upon the shaft C, outside the glass plate upon one side of the disk, is a ratchet G, with which co-operates a 30 pawl H, pivoted to the upper end of a lever I, which in turn is pivoted near its middle upon a screw-stud J, entering the upright portion A of the outer half of the casing. A spring K, connected to the pawl and to the 35 lever I, presses the pawl into engagement with the ratchet, while a spring L, secured to the casing and to the lower end of the lever I, tends to pull the latter forward against a stop-pin M upon the casing. The lower end 40 of the lever I extends down through the opening B in the top of the drawer-compartment into position to be struck by one of the cross-partitions N of the sliding money-drawer O. This drawer is or may be provided with the 45 usual or any suitable locking device arranged to be automatically released by the operation of any one of the keys of the machine and having behind it a spring which will throw it outward when so released. When the drawer 50 is closed, the partition N, Fig. 2, will hold the lever I in the position shown by the dotted lines, and when the drawer is released and opened the spring L will pull the lower end of the lever I forward against the stop M, causing the 55 upper end of the lever to be turned rearward and the pawl H to be lifted and engaged with another tooth of the ratchet G. When the drawer is now pushed inward, its partition N will strike the lower end of the lever I and 60 throw it rearward to the position indicated by the dotted lines, thereby throwing forward its upper end and causing the pawl H to turn the ratchet G and disk D with its attached plates F. A holding-pawl P, engaging the ratchet 65 G, prevents backward movement of the latter and disk.

From the foregoing description the follow-

ing explanation of the operation of the device will be clearly understood. When a coin is received in payment, the clerk will operate the 70 machine to indicate and register the amount of the sale and will drop the coin into the open mouth A' of the display and will take any change that may be required from the cash-drawer, which has either opened automatically or which he will pull open for that purpose. When he closes the drawer, the disk D will be turned to carry the receptacle E, into which the coin has been dropped, away 80 from the receiving-mouth of the casing and another receptacle E will be brought into position to receive a coin. At the next operation of the machine the coin deposited will enter this second receptacle E and the closing of the drawer will cause such receptacle 85 to be carried away from the receiving-mouth A' and the third receptacle be brought into position to receive a coin. At the two succeeding operations of the machine the third and fourth receptacles E will each receive a 90 coin and be carried around past the receiving-mouth A', while the receptacle E, which received the first coin, will be carried around to the position of the lowermost one in Fig 2 and will drop its coin through the opening B 95 into the money-drawer. At the next operation of the machine the coin contained in the second receptacle E will be dropped into the money-drawer, and so on continuously, each coin received being held exposed to view 100 during two succeeding operations of the machine. In this manner a coin received from a customer is carried out of reach of the clerk or cashier as soon as the money-drawer is closed, but is held exposed to view, so that if 105 any question arises as to what the coin was when the clerk hands the customer his change or fails to hand him any the coin will be in view and settle the question.

As stated at the beginning of the specification, the particular construction and arrangement of the various parts may be varied without departing from my invention.

So far as I am aware, I am the first in the art to construct a coin-displayer consisting of 115 a frame or casing, a revolving disk or receptacle-frame journaled therein and provided with holes or recesses or other suitable receptacles for the coins, and a transparent plate or plates for covering said receptacles at 120 either one or both sides of the disk, for the purpose described, and my claims, therefore, are not intended to be restricted beyond the terms in which they are expressed.

Having thus fully described my invention, 125 I claim—

1. A coin-displayer consisting of a frame or casing provided with receiving and discharging openings, a revolving disk journaled therein and provided with receptacles for the coins, 130 adapted to receive them at the receiving-opening and deliver them at the discharging-opening, and a transparent covering for the receptacles at one side of the disk, through

which the coins contained in them may be observed, and means for revolving the disk to bring its coin-receptacles successively to the receiving and discharging openings, substantially as described.

2. A coin-displayer consisting of a frame or casing provided with receiving and discharging openings for the coins, a revolving disk journaled therein and provided with receptacles for the coins, adapted to receive them at the receiving-opening and deliver them at the discharging-opening, and a transparent covering for the receptacles, secured at one side of the disk, through which the coins carried by the latter may be seen, and means for revolving the disk to bring its coin-receptacles successively to the receiving and discharging openings, substantially as described.

3. A coin-displayer consisting of a frame or casing provided with receiving and discharging openings for the coins, a revolving disk journaled therein and provided with a series of holes or recesses intersecting its periphery and adapted to receive the coins at the receiving-opening and deliver them at the discharging-opening, a transparent covering at one side of said disk, through which the coins carried by it may be seen, and means for revolving the disk to bring its coin-receptacles successively to the receiving and discharging openings, substantially as described.

4. A coin-displayer consisting of a frame or casing provided with receiving and discharging openings, a revolving disk journaled therein and provided with a series of holes intersecting its periphery and adapted to receive the coins at the receiving-opening and deliver them at the discharging-opening, and two transparent plates secured upon the opposite sides of the disk, through which the coins carried by the latter may be seen, and means for revolving the disk to bring its coin-receptacle successively to the receiving and discharging openings, substantially as described.

45 5. The herein-described coin-displayer, con-

sisting of the casing having the receiving and discharging openings, the disk D, journaled therein and provided with the circular openings E, intersecting its periphery and co-operating with the receiving and discharging 50 openings, the glass plates F, secured upon opposite sides of the disk D, the ratchet G, applied to the disk, the pawl H, and means for actuating the pawl to turn the ratchet and disk, substantially as described.

6. The combination, with a cash-register provided with a movable money-drawer, of a coin-displayer consisting of a suitable frame or casing provided with receiving and discharging openings, a revolving disk journaled 60 therein and provided with receptacles adapted to receive the coins at the receiving-opening and deliver them at the discharging-opening, and a transparent covering for the receptacles at one side of the disk, through which the coins 65 contained in them may be seen, and connections between the movable money-drawer and the revolving disk for turning the latter by the movements of the former, substantially as described.

7. The combination, with a cash-register having a backwardly and forwardly sliding money-drawer, of a coin-displayer consisting of a suitable frame or casing provided with receiving and discharging openings, a revolving disk 75 journaled therein and provided with receptacles adapted to receive the coins at the receiving-opening and deliver them at the discharging-opening, a transparent covering for the receptacles at one side of the disk, through 80 which the coins contained in them may be seen, a ratchet for turning the disk, an actuating-pawl for the ratchet, and a lever co-operating with said pawl and with the sliding money-drawer, substantially as and for the 85 purpose described.

THOMAS CARNEY.
